BOX FEEDING DEVICE FOR LIDDERS

Gerald C. Paxton, Sanger, Calif., assignor, by
mesne assignments, to Food Machinery Cor-
poration, a corporation of Delaware

Application May 24, 1932, Serial No. 613,225

4 Claims. (Cl. 1—10)

My invention relates to article handling apparatus and more particularly to mechanism for feeding boxes to a lidder or other processing device.

5 While useful with suitable modification in many industries, I will describe my invention with particular reference to its utility in the citrus industry. In citrus packing houses the fruit is packed in shipping boxes by hand and 10 the packed boxes are then usually collected on a horizontal conveyor system and delivered to a single point where they are lidded by an automatic lidding machine.

It is an object of my invention to provide an 15 automatic box feeding mechanism which is controlled in conjunction with the normal operation of the lidding machine, thus eliminating the necessity of manually feeding boxes from the conveyor to the lidder.

20 It is common practice in the citrus industry to strap the packed boxes immediately after the lids are applied, the lidding and strapping operations being performed by one machine or separate lidding and strapping machines placed side by 25 side in line with the packed box conveyor.

A certain machine manufactured by Hale Paxton, and known as the Paxton lidding and strapping machine, accomplishes the lidding and strapping operations simultaneously. In this 20 machine, the lid and the strap are both fed by hand into the machine prior to each operation.

It is another object of my invention to provide an automatic box feeding mechanism for delivering boxes to a machine for lidding and/or strapping boxes, and which is adapted to be controlled in conjunction with the feeding of lids and/or straps to the machine, so that a box is fed into the machine promptly after the machine is supplied with the material to be applied to said 40 box.

The manner of accomplishing the foregoing objects, as well as further objects and advantages, will be made manifest in the following description taken in connection with the accompanying drawings, in which:

Fig. 1 is a front elevational view of a preferred embodiment of my invention shown in conjunction with a Paxton lidder and strapper.

Fig. 2 is a fragmentary perspective view of a 50 Paxton strapper illustrating another mode of controlling the operation of my invention.

Fig. 3 is a plan view of the apparatus of my invention taken on line 3—3 of Fig. 1.

Fig. 4 is a longitudinal sectional view taken 55 on line 4—4 of Fig. 3.

Fig. 5 is a vertical sectional view taken on line 5—5 of Fig. 4.

Fig. 6 is a diagrammatic view of the electrical system employed in my invention and comprising the compound control means thereof.

Referring specifically to the drawings, a feed conveyor 10, comprising a preferred embodiment of my invention, is shown in Fig. 1 positioned between a packed box conveyor 11 and a lidding and strapping machine 12.

As shown in Figs. 1, 3, 4, and 5, the feed conveyor 10 includes a suitable frame 20 having angle iron legs 21, horizontal transverse angle iron members 22 and 23, and longitudinal angle iron members 24 and 25, the ends of the latter being secured to the transverse members 22 and 23. Secured to the under sides of the members 24 and 25 at opposite ends of the feed conveyor 10 is a plate 30 and a motor supporting hanger 31.

Adjustably mounted in suitable holes in the angle iron members 24 and 25 are box aligning rails 32 and 33 which are held in any desired position by set screws 34. Rotatably mounted at suitable intervals on the upstanding sides of the angle iron members 24 and 25 are pairs of idle rollers 35, as best shown in Fig. 3. Journaled in suitable bearings 36 provided on the angle iron members 24 and 25 is a shaft 40 to which is keyed a pair of box conveying rollers 41, it being noted in Figs. 1 and 4 that the top level of the rollers 41 is disposed slightly above the top level of the idle rollers 35. Keyed to one end of the shaft 40 is a sprocket wheel 45.

Yieldably mounted on the transverse angle iron member 22 is an arm 50. The arm 50 is downwardly bent at one end to form a flange 51 and is provided at its opposite end with an arcuate portion 52. Extending through suitable holes in the flange 51 are cap screws 55, these being screw threaded into the transverse member 22.

Mounted on the cap screws 55 are compression springs 56 which yieldably urge the flange 51 of the arm 50 into contact with the upstanding side of the member 22. The normal position of the arm 50 is best shown in Fig. 4, it being noted that the arcuate portion 52 thereof extends above the level of the rollers 41. Mounted on the plate 30 directly below the arm 50 is a conventional button switch 60 which is positioned to be contacted by the arm 50 when the arm is depressed to the dotted line position shown in Fig. 4.

Secured to the hanger 31 is a combined electric motor 65 and a worm and gear speed reduction unit 66. This unit drives a sprocket 70 positioned in alignment with the aforementioned 50

55

sprocket 45. Trained about the sprockets 45 and 70 is a chain 71, the chain and sprockets being enclosed by a suitable housing 75. Secured to one side of the hanger 31 is a conventional magnetic switch 76.

The lidding and strapping machine 12, shown in Fig. 1, in conjunction with the feed conveyor 10, is substantially of the same type as is disclosed in the copending applications of Hale 10 Paxton for U. S. Letters Patent Serial Nos. 554,211 and 566,822.

The machine 12 includes a frame 80 to which is secured the feed conveyor 10. Slidable vertically on the frame 80 is a box supporting carriage 81 which is adapted to be raised and lowered by a hydraulic cylinder 82. Rotatably mounted on the carriage 81 are box conveying rollers 85 which are horizontally aligned with the rollers 35 of the feed conveyor 10 when the carriage 81 20 is at rest in its lowermost position.

Mounted on opposite sides of the frame 80 are brackets 90 which carry a plurality of lid nailing devices 91. Secured to the under sides of the brackets 90 are lid positioning bars 92 and end 25 tucking mechanisms 95.

Centrally mounted on the frame 90 is a strapper 97 which includes a strapping saddle bar 100 and strap supporting jaws 101 suspended therefrom.

Mounted on one of the lid positioning bars 92 30 by means of a bracket 105 is a conventional button-switch 106 positioned to be momentarily contacted by the end of a box lid 110 when the lid is being fed to the machine 12, as shown in full lines in Fig. 1.

35 Referring particularly to Fig. 6, the electrical apparatus and wiring system employed for controlling the feed conveyor 10 includes the button switches 60 and 106, the magnetic switch 76, the motor 65, and a suitable source of electrical current such as a generator 115.

The lid responsive button switch 106 is provided with a pair of terminals A and B, an arm C, and is adapted to be urged out of contact by a compression spring D. The box responsive 45 button switch 60 is identical with the switch 106, and is provided with terminals E and F, an arm G, and a compression spring H. The magnetic switch 76 is of conventional design including a magnet J, a pair of terminals K and L, and a 50 spring returned bar M which is adapted to be drawn against the terminals K and L by the magnet J. The magnet J is provided with suitable terminals N and O. The motor 65 is provided with conventional terminals P and R, and 55 the generator 115 with terminals S and T.

Terminals S and P are connected by a wire 120; terminals T and A by a wire 121; terminals A and K by a wire 122; terminals L and B by a wire 123; terminals N and S by a wire 124; terminals O and R by a wire 125; terminals F and L by a wire 126; and terminal E is connected to the wire 125 by a wire 127.

Operation

65 The usual manner of operation of the lidded and strapper 12 is as follows: Just before the lidding of each box it is necessary that a strap 136 and a lid 110 be fed into the machine, and in the type of machine illustrated this feeding is 70 done manually. The strap is usually fed by the left-hand and is inserted in the machine before the lid. In feeding the strap, it is lifted up beneath the saddle bar 100 with opposite ends of the 75 strap engaging the lower guide lugs of the

jaws 101, so that opposite ends of the strap become lodged in the lower ends of these jaws.

As soon as the strap has thus been inserted in the strapper 97 the lid 110 is swung inwardly in the right-hand so that this lid moves leftwardly 5 into the position in which it is shown in full lines in Fig. 1, after which the right-hand end of the lid is lifted, permitting it to assume the position in which it is shown in dotted lines in this view. It is to be noted that in its full line position, shown in Fig. 1, the lid 110 engages the switch 106 so as to actuate this, but that in its dotted line position the lid is out of contact with the switch.

With the lidded 15 and a lid, these are applied to a packed box by positioning this box on the supporting carriage 81 which is then elevated to press the lid onto the fruit and bring the ends of the lid against the ends of the box just beneath the nailing devices 91. These nailing devices and the strapper 97 are then actuated and the supporting carriage 81 with the lidded packed box automatically drops downwardly and the box, lidded and strapped, is discharged in a rightward direction 20 therefrom, as clearly explained in the copending application of Hale Paxton for U. S. Letters Patent, Serial No. 526,927, filed April 1, 1931.

25 The principal function of the present invention is to automatically feed packed boxes of fruit onto the supporting carriage 81 so that a packed box will be positioned on the carriage 81 in readiness for completing the lidding and strapping function with as little delay as possible after the strap and lid have been fed to the machine. The feed conveyor 10, therefore, is adapted to feed a packed box into the machine 12 in the following manner:

When a packed box 130 is discharged onto the feed conveyor 10 by the packed box conveyor 11, 40 it comes to rest in its dotted line position shown in Fig. 4 due to frictional engagement of the box with the rollers 41, these being normally locked against rotation by the worm and gear unit 66.

The packed box conveyor 11 is driven continuously by any suitable power means (not shown) and serves to deliver packed boxes from the packing table (not shown) to the feed conveyor 10. In common practice boxes are sufficiently spaced on the conveyor 11 to allow ample time 50 for the lidding operation without the boxes becoming congested at the delivery end of the conveyor 11. As the box 130 slides onto the conveyor 10 the arm 50 is depressed to its dotted line position shown in Fig. 4 and the switch 60 is 55 contacted, thus closing the circuit between the lid operated switch 106 and the magnet J through wires 126, 127, 123, and 125. When, after the switch 60 is thus closed, the switch 106 is momentarily contacted by a lid 131 during manual 60 placement of the lid in the lidding machine 12 (as shown in Fig. 1) this energizes the magnet J of the switch 76 bringing the bar M in contact with the terminals K and L, thus completing the circuit between the generator 115 and the 65 motor 65.

When thus energized, the motor 65 rotates the rollers 41 through the speed reduction unit 66 and the chain 71, and the box 130 is discharged from the feed conveyor 10 onto the box supporting carriage 81 of the lidding machine 12, as 70 shown in Fig. 1. As the box passes from the feed conveyor 10, the arm 50 returns to its normal position and the switch 60 breaks the circuit between the generator 115 and the magnet J, 75

and the bar M of the magnetic switch 76 then returns to its normal position and breaks the circuit between the generator 115 and the motor 65. It is thus evident that the conveyor 10 is 5 automatically stopped upon the opening of the box responsive switch 60 as the box passes into the lidder 12. It is also to be noted that closing of the switch 60 by a box riding over the lever 50 does not start the conveyor 10 in operation until 10 the lid responsive switch 106 is also contacted.

The feed conveyor 10 is thus seen to feed a box into the lidder and strapper 12 as the feeding of the strap and lid into this machine is being completed. Owing to the fact that the operation 15 of the conveyor 10 does not commence until the switch 106 is actuated, there is no danger of a box being prematurely fed into the machine. On the other hand, it is not necessary for the operator to consciously set the feed conveyor 20 in operation, as this is automatically accomplished in connection with the feeding of the lid into the lidder and strapper.

The essence of my invention is thus seen to reside in the compound control means illustrated 25 in Fig. 6 and operating in accordance with the description hereinabove.

Referring now to Fig. 2, a modified form of apparatus for controlling the feed conveyor 10 is here shown which includes a button switch 135 30 mounted on the saddle bar 100 of the lidding and strapping machine 12. The switch 135 is identical in character with the switch 106, and when the switch 135 is used, it is substituted in the electric system of my invention in the place of 35 the switch 106. The switch 135 is positioned to be manually operated simultaneously with the placing of a strap 136 in the saddle bar 100 as shown in Fig. 2.

The purpose of this modified form of my invention 40 is to start the operation of the feed conveyor 10 in connection with the feeding of the strap to the machine. The advantage of this is that certain operators are faster than others and are accordingly able to get a lid in position after 45 the feed conveyor has started to deliver a box to the lidding and strapping machine without inter-

fering with the delivery of this box to the machine. Where a worker having these qualifications is available, of course, it is advantageous to have the manual switch of my device in position on the strapping saddle bar 100 so that the switch can be actuated in conjunction with feeding the strap into the machine.

While I have shown and described but two preferred forms of my invention, it is to be understood that various changes can be made in these without departing from the spirit of the invention or the scope of the appended claims.

What I claim is:

1. In combination with a box lidder: a packed box conveyor adapted to deliver packed boxes 15 to said lidder; a feed control conveyor adapted to be interposed between said packed box conveyor and said lidder; means on said feed control conveyor to stop boxes discharged one at a time onto said conveyor by said packed box conveyor; means 20 on said feed control conveyor to discharge boxes one at a time into said box lidder; and means on said lidder responsive to the placement of a lid in said lidder to start said box discharge means 25 on said feed control conveyor.

2. In combination with a box lidder: a feed control conveyor normally dead; means for operating said conveyor; and a compound control means including means responsive to the positioning of the box on said conveyor and means responsive to the insertion of a lid in said lidder to set in motion said conveyor operating means to cause said conveyor to feed said box into said lidder.

3. A combination as in claim 2 in which said 35 box responsive means causes said compound control means to stop said conveyor when said box responsive means is disengaged by said box as the box is fed into said lidder.

4. A combination as in claim 2 in which said 40 lid responsive means accomplishes its function when contacted by said lid so that said compound control means maintains said conveyor in motion until said box has been fed therefrom.

GERALD C. PAXTON.
